UNITED STATES PATENT OFFICE.

DAVID ASHMAN, OF BALTIMORE, MARYLAND, ASSIGNOR TO EAGLE MANUFACTURING CO.

POWER-TRANSMITTING DEVICE.

SPECIFICATION forming part of Letters Patent No. 653,636, dated July 10, 1900.

Application filed January 25, 1900. Serial No. 2,735. (No model.)

To all whom it may concern:

Be it known that I, DAVID ASHMAN, a citizen of the United States, residing at Baltimore, in the State of Maryland, have invented 5 certain new and useful Improvements in Power-Transmitting Devices, of which the following is a specification.

This invention relates to mechanism for transmitting power to drive-wheels, especially 10 designed to actuate sewing or other machines which are usually propelled by means of pedals.

Referring to the drawings, Figure 1 is a section view, in side elevation, of a machine-frame 15 equipped with my improvements. Fig. 2 is a view in front elevation of the same. Fig. 3 is an interior view of the clutch. Fig. 4 shows two views of the clutch-cap. Fig. 5 is a diametrical section view of the clutch.

20 Two upright stands A A' are secured to a vertical rectangular frame B by screws or bolts, the frame constituting a brace for the structure. A fender C for the drive-wheel is also secured to the rectangular frame on one 25 side and projects on the outside of the stand A'. The top brace-rod a of the frame B has three downward-projecting lugs b b' b'', and an arm or bracket b''' is supported by the top brace and side of the frame.

30 A horizontal shaft D is parallel with the top of the frame and has one of its ends revoluble on a pivot-bearing c at one side of the frame B. The other end of the shaft passes through the opposite side of the frame and 35 the stand and is revoluble on another pivot-bearing c' in the fender C. Keyed to one end of this shaft outside of the upright stand A' and inclosed by the fender is a drive-wheel F. Two friction-clutches G G' are mounted

40 securely on the shaft D between its ends. Two swinging treadle-arms d d' are used. Each of these arms has a pivot-bearing e e', the one in the downward-projecting lugs b b' and the other in the downward-projecting lug b'' and the side of the bracket b'''. The treadles 45 are provided with pedals f f'. Each treadle near its upper end is provided with a frame g g', which curves concentric with the pivot-bearings e e', and the upper and lower edge 50 within the frames is provided with ratchet-teeth i i'. Each friction-clutch G G' consists

of a circular disk provided with a circumferential wall h, and a hub h' projects on each side of the disk concentric with the wall and has a bore h² to take over the shaft D, to 55 which it is secured by a set-screw h³. A collar l has a lug m and takes loosely but closely around the hub h' within the disk, and pivoted to the lug is a clutch-pawl having at one end a lip n', projecting beyond the lug and 60 which impinges by frictional engagement the inner surface of the circumferential wall of the disk when the latter is turned by the shaft in the direction of the arrow; but when it is turned in the opposite direction the lip n' will 65 be released from frictional engagement with said wall and the disk may be turned free of the lip n'. The pawl also has at the other end a tongue n². An L-shaped arm o is pivoted at o' to this end of the pawl, so that the 70 shorter end of the arm is parallel with the said tongue n² and leaves a space between. The longer end of the arm o is connected by a spiral spring r to an ear l' on the collar l. This spring normally draws on the L-shaped arm o, 75 so as to compress or grip a pin which passes into the space, as will presently be described. The cap of this clutch device consists of a circular plate P, which is loose on the shaft D and revolves against the wall h of the disk 80 and on one side of which is a cogged hub p, concentric with the circumference of the plate and is provided with an end shoulder p'. The other side of this plate has a projecting pin t, which passes into the said space between 85 the tongue n² and the arm o to actuate the clutch-pawl within the disk when the cogged hub is turned by the movement of the frame, and the pin is held compressed between the tongue and arm o by the tendency of the 90 spring r. This arrangement prevents the pin t from rattling within the said space, and the spring also serves to return the clutch-pawl to its normal impinging position against the wall of the disk when it has been thrown out 95 of such position by the backward movement of the pin t on the cap when the latter is rotated reversely. This cap is held in place by a collar u, secured to the shaft by a set-screw u' and which bears against the shoulder p' to 100 hold the cap up to the wall of the disk. One series of teeth only, either i or i', of the curved

frames $g\ g'$ engage the cogged hub on the cap P to turn the latter right and left. When the cap is turned to the left, the pawl will impinge frictionally on the inner surface of the wall 5 of the disk and cause said disk and shaft D to rotate, the disk continuing to revolve while the cap-plate P and pawl are brought back by the reversed swinging movement of the concentric tooth-frame to reimpinge the said wall.

In machines manufactured at the present time some are built to run in one direction only and others in the reverse direction only. This is particularly true of sewing-machines 15 as used in factories. For this reason it is desirable that driving mechanism for such machines shall be provided that is reversible, so as to be adapted to be attached to machines that are intended to run in opposite directions. The mechanism of this clutch is therefore reversible—that is, may be taken out of the cup-shaped disk and set in again in reverse position, so as to impinge the wall of the disk either right or left, as desired. The 20 curved frame g is adjustable upon the treadle-arm by means of slots $j\ j'$ and screws $k\ k'$, (shown in Fig. 1 by broken lines,) so as to allow the upper series of teeth i of the frame to take down on the cogged hub or the lower series i' of teeth to take up under the hub, as desired.

The operation is as follows: The treadle-arms $d\ d'$, carrying the concentric frames $g\ g'$, are oscillated rearward and forward alternately in order that the positive actuating effect of the frames upon the cogged hubs of the clutches may be differential in respect to each other, so that when one treadle is forced forward it will cause the frame secured thereto to rotate the cogged hub and cap P , and the pin on this cap will push the clutch mechanism and cause it to impinge the wall of the disk and rotate the latter and the shaft. Thus the momentum acquired in the forward 45 rotation of the shaft and drive-wheel will be retained until succeeded by the positive action of the clutch operated by the other treadle, which will cause the continuous motion of said shaft and wheel.

50 Having thus described my invention, what I claim as new, and desire to secure by Letters Patent, is—

1. In clutch mechanism for transmitting rotary power, the combination of a support-

ing-frame; a rotary shaft supported in said frame and carrying a drive-wheel; a cup-shaped friction-disk on said shaft between its ends; a cap, P , loose on said shaft and closing the cup-shaped disk and provided on one side with a cog by which it is driven and on the other side with a pin which projects into the said cup-disk; a clutch-pawl device which may be placed in reverse positions within said cup-shaped disk and be actuated by the said pin, whereby the position of the clutch-pawl may be reversed within the cup-disk and the shaft may be driven in one direction or the other.

2. In a friction-clutch for power-transmitting mechanism to rotate drive-wheels, the combination of a shaft carrying the drive-wheel; a disk having a circumferential wall, h , and which is secured to a shaft; a loose collar, l , having a lug, m , clutch-pawl, n , pivoted on said lug and at one end having a lip, n' , to impinge by frictional engagement the inner surface of the circumferential wall, a tongue, n^2 , on the other; an L-shaped arm, o , pivoted to said pawl and forming a space between it and said tongue; a cap, P , loose on said shaft having a pin, t , which takes into the said space; and a spiral spring, r , connecting the said arm with the collar and serving to compress or grip the said pin, t , in the space.

3. The herein-described reversible rotary mechanism consisting of the combination of a supporting-frame; a rotary shaft supported in said frame and carrying a drive-wheel; cup-shaped friction-disks on said shaft; reversible clutch-pawl mechanism within said cup-disks; a cap loose on said shaft and provided on one side with a cog and on the other side with a pin which engages the reversible pawl mechanism; and treadles swinging in said frame and each having two racks one of which to engage the cog on said loose cap to turn the cap in one direction, and the other rack to engage said cog to turn the cap in the opposite direction when said clutch-pawl mechanism has been reversed in the cup-disk.

In testimony whereof I affix my signature in the presence of two witnesses.

DAVID ASHMAN.
